By *Watson E. Coleman*
Attorney

UNITED STATES PATENT OFFICE.

JOHN W. WHIPPLE, OF CUSHING, OKLAHOMA, ASSIGNOR OF ONE-HALF TO JOSEPH V. BAILEY, OF CUSHING, OKLAHOMA.

PENCIL-VENDING MACHINE.

Application filed February 19, 1925. Serial No. 10,352.

This invention relates to vending machines, and particularly to machines for vending pencils and like articles.

The general object of the invention is to provide a very simple and effective machine for this purpose so constructed that upon the deposit of a proper coin a single pencil will be vended.

A further object is to so construct the machine so that the machine will vend two kinds of pencils each upon the deposit of a proper coin.

A still further object is to provide a mechanism of this character which does not require the use of complicated mechanism which is liable to get out of order, and in which the magazines containing the pencils may be shifted out of the outer casing to permit the magazines to be filled.

Other objects have to do with the details of construction and arrangement of parts as will appear more fully hereinafter.

My invention is illustrated in the accompanying drawings, wherein:—

Figure 1 is a perspective view of a pencil vending machine constructed in accordance with my invention;

Figure 2 is a fragmentary sectional perspective view of the machine showing the interior construction;

Figure 3 is a fragmentary vertical sectional view from front to rear;

Figure 4 is a perspective view of the means for supporting the magazines;

Referring to these drawings, 10 designates a casing which is preferably made of metal, though any other suitable material may be used, one side of the casing being cut away, as at 11, to accommodate a money drawer 12, this drawer, when closed, being locked to the casing itself by any suitable locking device as, for instance, a padlock passing through the hasp 13. The top of the casing is closed by a lid 14 held locked in any suitable manner, as by means of a hasp and padlock, and the back of the casing is preferably provided with upwardly extending ears 15 whereby the casing may be mounted upon a wall if desired. The bottom of the casing is preferably flat so that the casing may also be mounted upon a counter. The front of the casing is provided with a transparent pane 16 and with a discharge slot 17 having a length equal to that of a pencil, and extending through this discharge slot is a chute

18 formed exteriorly to the front of the case with a pencil-receiving shelf 19.

To one side of the case there is disposed a coin slot 20 and at the opposite side of the case on the front thereof is a coin slot 21. The coin slot 20 is for the reception of coins of one denomination and the slot 21 for the reception of coins of another denomination.

Disposed within the casing 10 and supported in any suitable manner, as will be later described, are the two pencil containers or magazines 22 and 23, the bottom of each magazine extending downward to a medially disposed, longitudinally extending aperture 24 defined by downwardly extending side walls. Disposed below each of the magazines 22 and 23 are the pencil vending rollers 25 and 26. These rollers may be made of wood, metal or any other suitable material and are mounted upon a yoke 27 which is riveted, bolted or otherwise attached to any suitable support as, for instance, riveted to the back and end walls of the casing 10. Each of these rollers is formed with a longitudinally extending groove 27^a having a length sufficient to receive a pencil *a* from the corresponding magazine when the groove is brought up into coincidence with the mouth of the magazine. A spring 28 associated with each roller is attached to the roller and to the wall of the casing or other suitable support and resists any rotation of the roller from a position with the groove 27 in coincidence with the mouth 24 into a discharging position.

Each roller has a separate actuating means, and I have shown this actuating means for each roller as consisting of an operating rod 29 extending through the front of the casing and projecting beyond the same and passing through a small housing 30 which contains the coin control mechanism. Attached to this operating rod or plunger 29 is a chain or like flexible element 31, which in turn is attached to the roller 25 or 26. It will be seen, therefore, that when the plunger 29 is forced inward, the chain will pull upon the roller and cause the roller to rotate against the action of the corresponding spring 28 in a direction to carry the pencil contained within the groove 27 downward and forward and discharge it onto the chute 18. This chute 18 extends upward beneath the roller 25 and the rear end of the chute approximates the roller 110

26 so that when either the roller 25 or 26 has rotated to a degree sufficient to permit the pencil to drop out, the pencil will drop out upon the chute 18 and will roll down 5 the same and be deposited in the cup or receiver 19. Of course, immediately that the pressure upon the plunger 29 is released, the spring 28 will act to return the roller to its initial position with the groove 27 10 again in alignment with the mouth 24 and another pencil is deposited in said groove, and it will be obvious that as soon as the groove 27 has passed the mouth 24, the surface of the roller will close the discharge 15 opening of the magazine and no more pencils will be discharged.

I have not illustrated the coin control mechanism disposed within the housing 30 and which prevents the inward movement 20 of the plunger 29 until a proper coin has been deposited in one or the other of the slots 20 and 21 for the reason that there are a number of coin control mechanisms which may be used in conjunction with the 25 plunger 29 and which are upon the market, and for the further reason that the particular coin control mechanism forms no part of my present invention.

The magazines 22 and 23 are removable 30 through the top of the casing upon opening of the lid and the downwardly extending flanges 24 which define the mouth of each magazine fit between a pair of supporting irons 32 whose extremities are upwardly bent and fastened to the end walls of the casing, these supporting irons being preferably connected by cleats 33. Thus it will be seen that when the magazine is disposed in place it is firmly supported by 35 means of this pair of supporting irons engaging the flanges 24, but that the magazines may be readily removed, filled with pencils, and then put back again, this being an easier method of filling the magazines than if it was necessary to leave the magazines within the casing and fill them, as this permits an employe to go from vending machine to vending machine, removing the empty magazine, replacing them with 40 full magazines, and carrying the empties to a filling station.

The operation of my mechanism will be obvious from what has gone before. Preferably the front magazine 22 has a transparent front wall 22^a through which the contents of the magazine may be observed, though this obviously is not entirely necessary. The front magazine preferably contains pencils which may be vended at the 45 price of five cents and upon the insertion of a nickel in the slot 20 and the arrival of the nickel at the housing 30 the plunger 29 is released and upon being pressed inward draws, through the chain 31, the roller 25 in a counterclockwise direction until the

groove 27 discharges the pencil upon the chute 18, whereupon the pencil rolls down said chute into the tray 19. As soon as the pencil is discharged upon the tray, which operation may be seen through the glass pane 16, the plunger may be released, whereupon the spring 28 will draw the roller back to its initial position and a new pencil will drop from the magazine into the groove 27. The same operation, only involving the insertion of a different coin in the slot 21, will secure a pencil from the magazine 23 which is designed to contain pencils selling at one cent.

Preferably, though this forms no part of my invention, I provide a pencil sharpener 34 mounted upon one wall of the casing so that the vended pencils may be sharpened right there and then.

It will be seen that the operating mechanism for this vending machine is very simple and one with which almost everybody is entirely familiar. The different parts of the vending machine are very simple and fit snugly so as to make the whole machine 85 compact and yet there is no friction between the parts.

I claim:—

1. A pencil vending machine comprising a casing having a discharge slot, a coin receiving slot, a magazine mounted within the casing and having a hopper-shaped bottom defining a longitudinally extending discharge slot, a roller disposed within the casing below the magazine and having a groove adapted to align with said slot, means for actuating the roller including a plunger, a flexible connection attached to the plunger and to the roller and adapted thereby to cause the rotation of the roller when the plunger is forced inward to thereby carry the slot of the roller from a receiving to a discharge position to discharge the pencil therefrom, a spring acting to return the roller to its initial position, and a chute receiving the pencil when it is discharged from the roller and discharging it through the discharge slot of the casing.

2. A vending machine of the character described including a casing having a discharge opening and a coin chute opening, a magazine disposed within the casing and having a hopper-shaped bottom formed with a longitudinally extending discharge slot, a roller mounted below the magazine and having a longitudinally extending groove adapted to receive a pencil discharged through said slot in the magazine, means for shifting the roller in one direction comprising a plunger, a flexible connection extending from the plunger to the surface of the roller and being attached thereto at one point, coin actuated means for preventing the movement of the plunger without the introduction of a coin into the slot, and a

chute upon which the pencil is discharged, the chute extending out through the discharge opening in the casing and being formed to constitute a tray.

- 5 3. A pencil vending machine including a casing having a door at its top, a magazine supported within the casing and having a contracted lower end, manually operable means for discharging pencils one by one
10 from the magazine, and a supporting means for the magazine attached to the casing and upon which the magazine rests, the magazine being vertically movable out of engagement with the supporting means and out through
15 the top of the casing, said supporting means including parts embracing the contracted lower end of the magazine.
4. In a vending machine, a casing having a discharge opening, a magazine disposed
20 within the opening, coin actuated means disposed below the magazine and adapted to receive an article therefrom and discharge it through the discharge opening of the casing upon the deposit of a coin, and means for
25 supporting the magazine comprising a pair of longitudinally extending bars attached at their ends to the walls of the casing, the

magazine at its lower end having a discharge slot defined by downwardly extending flanges adapted to fit between the longitudinally extending bars of the magazine. 30

5. In a vending machine, an outer casing having an article discharge slot, a magazine disposed within the casing and having a hopper-shaped bottom formed with a longitudinally extending discharge slot, a roller operatively supported immediately beneath the magazine and having a longitudinally extending slot coinciding with the slot in the magazine, the surface of the roller closing 35 the slot of the magazine when the roller is turned to carry its groove away from the slot, a spring normally urging the roller into a position with its groove in alignment with the discharge slot of the magazine, an actuating plunger extending through the front of the casing, and a chain attached to the plunger and to the roller and acting, when the plunger is forced inward, to rotate the roller in a direction against the action of 40 said spring. 45

In testimony whereof I hereunto affix my signature.

JOHN W. WHIPPLE.
